(57) CLAIM

The ornamental design for a display screen or portion thereof with electronic icon, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of a display screen or portion thereof with electronic icon, according to a first embodiment;

FIG. 2 is a front view of a second embodiment thereof;

FIG. 3 is a front view of the electronic icon of the first and second embodiments, shown without a display screen for ease of visibility;

FIG. 4 is a front view of a third embodiment thereof;

FIG. 5 is a front view of a fourth embodiment thereof; and,
FIG. 6 is a front view of the electronic icon of the third and fourth embodiments, shown without a display screen for ease of visibility.

The broken lines illustrate the display screen or portion thereof and form no part of the claimed design.
